UNITED STATES PATENT OFFICE.

WILLIAM H. CHAPMAN, OF PORTLAND, MAINE.

CONTROLLER FOR ELECTRIC MOTORS.

SPECIFICATION forming part of Letters Patent No. 707,300, dated August 19, 1902.

Application filed March 12, 1902. Serial No. 97,900. (No model.)

To all whom it may concern:

Be it known that I, WILLIAM H. CHAPMAN, a citizen of the United States of America, and a resident of Portland, Cumberland county, 5 State of Maine, have invented certain new and useful Improvements in Controllers for Electric Motors, of which the following is a specification.

The object of my present invention is to 10 provide a controller for electric motors by which any speed may be obtained from nothing to maximum and by which the motor may be reversed and to avoid complete interruption of the working circuit of the motor, 15 and so do away with sparking at contact-surfaces, which is liable to stick the contact-surfaces together by welding. I accomplish my purpose by means of rheostats with numerous steps of resistance and these steps representing a fine gradation from maximum to 20 minimum current.

The usual practice in controlling motors is to use a switch for making and breaking the circuit, and if the motor is to be reversed a 25 special reversing-switch also is used, and these switches are operated to interrupt the whole current of the motor at its maximum, and a rheostat also is used of only wide enough range to cut down the current of starting to 30 the normal current which the motor is supposed to use. My controller, on the contrary, without the use of switches starts and stops the motor and reverses it by means of rheostats constructed to admit current gradually 35 by fine gradations and in one direction or the other through the armature of the motor.

I illustrate my invention by means of the accompanying drawings, in which—

Figure 1 is a front elevation of my controller with the connections shown diagrammatically. Fig. 2 is an enlarged section through the switchboard, and Fig. 3 is a detail of the spring which centers the rheostat-arms.

45 B, C, B', and C' are four sets of rheostat-segments, composed of thin copper sheets separated by mica and all clamped together by screws in the iron supporting-frames A A', from which they are insulated by mica in 50 the usual manner. Each set of rheostat-segments is connected in the usual manner to a series of resistance-coils, (not shown), and the

resistance of these coils in the successive steps increases by regular gradations from the outer extremes of each set toward the inner extremes, which are located at the center portion of the supporting-castings A A'. While the outer steps of resistance may be, say, three one-hundredths ohm, the inner steps are as high as thirty ohms each, and 60 between these two extremes are all gradations. In practice I find that the steps should be such as will represent not much over one hundred watts—that is, the square of the current multiplied by the resistance of a step 65 should not be much over one hundred. By following out this rule I obtain a rheostat which is practically sparkless from one extreme to the other.

The rheostats here shown are of the type 70 which I may term "differential" rheostats—that is, those in which as the arm moves from the center toward one end the resistance in one direction increases in the same proportion as it decreases in the other direction. 75

D and D' are inverted-L-shaped levers or rheostat-arms, each pivoted at G G' on a metallic stud. The vertical portion of these levers have brass fingers pivoted to them and actuated by springs s to press them into contact with the segments B B' and C C'. The lever D has an inwardly-projecting hub, Fig. 2, on which the levers E E' are mounted and clamped. These levers have fingers c c', pressed by springs into contact with the set 80 of circular segments 1 2 3 4 5, which are mounted on the slate F. The levers D D' are connected so that they move simultaneously. As here shown, they are linked together by the connecting-rod H, pivotally 85 connected to the levers by studs which are insulated electrically from the levers, as shown in Fig. 2. On the lever D' is a metal finger c', pressed by spring into contact with the segments 6 7 8 9 10, mounted on the slate F. 90 Means are provided for bringing the levers D and D' back to a central or normal position when they are free to move. For this purpose I provide a pair of coiled springs s', one on each end of the rod S, one end of the rod 95 being pivoted to a stud s', projecting out from the slate, and the center of the rod between the two springs slides through a socket s', that is pivoted to the horizontal portion d'

of the lever D. Thus the tendency of these two opposing springs s' is to bring the arm d^2 to a central position on the rod. Solenoids are provided for operating the levers D and D' to slide the contact-fingers along the rheostat.

The horizontal ends d^2 d^3 of levers D and D' are pivotally connected with the links II', and these in turn are pivotally connected to 10 the iron cores J J' of two solenoids K and K', which are mounted in an iron casing k, attached to the slate F. At the tops of the two solenoids are air dash-pots L L', arranged to resist the movement of the cores upward, but 15 not downward. The piston l has ports l^4 , controlled by loose disk-valves l^2 , fitting over the stem l^3 , which closes the ports when the piston goes up and allows them to open when the piston goes down. In the lower half of 20 the dash-pot are grooves l^1 and an opening l^5 , so that the piston moves freely both up and down when it is in the lower portion of the dash-pot. In the solenoid-circuit is placed an emergency-rheostat, by which 25 resistance is inserted in the circuit when there is an excessive current over the main line.

At M is a solenoid whose iron core is supported by a spring e under compression. The upper end of the core is pivotally connected 30 to a lever which operates over a rheostat or series of contacts connected to the set of resistance-coils R. Under normal conditions the spring holds the core up and keeps the lever f in one position on the upper contact 35 of the series; but when this solenoid is excessively strong it overcomes the spring e and pulls the lever f to some lower portion of the series of contacts. The screw g serves to adjust the compression of the spring e, so that 40 a greater or less current is required in the solenoid in order to pull the lever f down from its normal position on the top contact-point.

In directing the operations of my controller I make use of a differential rheostat located in any convenient place to be manipulated by an attendant and connected by three wires with the controller proper. This rheostat is composed of a metal lever N and 45 contact-segments O, connected to suitable resistances, and their resistances are so distributed that when the lever is in the central position it introduces an equal resistance between its point of contact and the two ends 50 and in other positions an unequal resistance, which becomes more unequal as either end segment is approached. When contact is made with an end segment, the resistance is all cut out of that side and all inserted in the 55 other side. One end segment is connected with one terminal of solenoid K and the other end segment to one terminal of solenoid K', and the other terminals of these two solenoids are connected to one line-terminal, while the 60 lever N is connected to the other line-terminal through the wire m, in which, however, more or less of the resistance R is inserted 65

whenever the lever f is pulled down. The effect of the insertion of resistance R is to weaken the force of both solenoids, allowing 70 the spring on rod S to bring the levers D D' nearer the central position.

T is the service-switch, which is kept closed during the hours of service of the motor to be controlled. From this switch the current 75 is distributed by wires to the various circuits of the controller, which may be classified as follows: the armature-circuit, the shunt field-circuit, the controlling-solenoid circuit, and 80 the brake-solenoid circuit. This latter circuit is used when the motor is applied to elevator work where a friction-brake is used to stop the motion and the brake is released by a solenoid. In the armature-circuit is included 85 the solenoid M, lever D, resistances at B or C or such portion of them as is not cut out by the contact-fingers b and lever D, resistances at B' or C' or such portion of them as is not cut out by fingers b' and lever D', and the series 90 winding of the motor with the armature. In 95 the shunt field-circuit is included the shunt field-winding of the motor, one or more of the segments 6 to 10, the finger c², lever D', and the series field-winding, and when the lever D is at its middle position or on any of 100 the three central segments it also includes one or more of the resistance-coils t. The controlling-solenoid circuit has two branches, one of which includes the winding of the solenoid K and one end segment of the series 105 of segments O, whatever resistance there is between this segment and the contact-point of the lever N, lever N, wire m, and when there is excessive load also part or the whole of resistance R. The other branch of the 110 solenoid-circuit includes winding of the solenoid K', the end segment at the other end of the series of segments O, whatever resistance there is between the end segment and the contact-point of the lever N, the lever N, 115 wire m, and when there is excessive load also part or the whole of resistance R. The brake-solenoid circuit includes the winding on 120 solenoid M, the hub of lever D, one or the other of levers E or E', one or the other of the segments 1 2 3 4 5, and the winding of the brake-solenoid.

The operation may be described as follows: When the lever N is in its middle position, a very weak current is admitted equally to both 125 solenoids K and K' through the very high resistance of the coils located at the center portion of the series of segments O. When the motor is to be started, the lever N is moved to one extreme of the series of segments— 130 say to the right. This removes all resistance from the branch circuit of solenoid K, and this solenoid then pulls its core J upward and this causes the levers D and D' to move toward the right. While these levers are in the central position, all the resistance at B, C, B', and C' is in the armature-circuit and allows 135 only a very feeble current to flow through the resistances and none through the arma-

ture. When the levers D and D' arrive at the extreme end of the series of segments—for instance, to the right—all resistance is cut out and the armature-circuit receives its full current, said current passing through wires 13 14 15 and thence through the lever D'. The movement of the levers to the right is retarded by the dash-pot L, and thus the current is admitted gradually to the armature, which is caused to rotate, the shunt field-circuit being energized to its full extent as soon as finger c' arrives at segment 10, which is considerably before the levers D and D' reach their limit. The current comes from the plus-pole by wire 18 through the shunt-winding, wire p, segment 10, finger c', lever D', wires 16 q, series-winding, wire q', and thence to negative pole. To stop the motor, the lever N is brought to central position, solenoid K becomes weakened and equal to solenoid K', so that the spring on rod S brings the levers D D' back to central position, where the armature gets no current. To start the motor in the reverse direction, the lever N is turned to the other extreme end of its range, where it cuts out all resistance from the circuit of solenoid K'. This solenoid then draws up its core J' and moves the levers D D' to the left, and the movement is retarded by the dash-pot L'. Current is thus admitted to the armature in a reverse direction and gradually brought to full strength. The current passes down lever D, wire 14, through the armature, wires 13 17, through lever D, &c. When the lever N is brought to the center, solenoid K' loses its force and becomes equal to solenoid K, and the spring on rod S brings the levers D D' back to the central position. After the motor is started if it is desired to change its speed this may be done by proper manipulation of the lever N, which the operator soon becomes accustomed to. By moving the lever N to intermediate positions the relative strengths of solenoids K and K' may be nicely adjusted, so as to make the levers D and D' take up intermediate positions, and thus introduce more or less resistance into the armature-circuit. If for any reason current is admitted too rapidly to the armature-circuit for the safety of the motor, the solenoid M acts to check it by inserting the resistance R, weakening the solenoid K and K', whichever one happens to be in action, and thus allows the levers D D' to come back to some position nearer the center, where the current will be reduced to proper limits. The current in the armature-circuit really undergoes a division through the resistances B, C, B', and C'. When the levers D D' are central, there is a very feeble current flowing through the resistances B C B' C' directly across from lever D to lever D' and none through the armature.

I claim—

1. In a controller for electric motors, the combination with the armature of a pair of differential rheostats each terminal of each rheo-

stat being connected with one armature-terminal, a rheostat-arm for each rheostat and means for operating said arms in unison with each other.

70

2. In a controller for electric motors, the combination with the armature of a pair of differential rheostats each terminal of each rheostat being connected with one armature-terminal, a rheostat-arm for each rheostat, a connecting-rod connecting the two arms and means for operating said arms.

75

3. In a controller for electric motors, the combination with the armature, of a pair of differential rheostats each terminal of each rheostat being connected with one armature-terminal, a rheostat-arm for each rheostat, a connecting-rod connecting said arms, a pair of solenoids, each adapted to throw said arms in opposite directions.

80

4. In a controller for electric motors, the combination with the armature, of a pair of differential rheostats each terminal of each rheostat being connected with one armature-terminal, an inverted-L-shaped rheostat-arm for each rheostat, a connecting-rod connecting said arms, a pair of solenoids connecting with the horizontal portion of said arms.

85

5. In a controller for electric motors, the combination with the armature of a pair of differential rheostats connected with the armature, a pair of connected rheostat-arms for said rheostats, a set of segments adjacent to one of said arms, a contact-finger on said arm adapted to slide on said segments, said segments being connected with the shunt-winding of the motor and said rheostat-arm connecting with the line-terminal.

90

6. In a controller for electric elevator-motors, the combination with the armature, of a pair of differential rheostats connected with the armature, a pair of connected rheostat-arms for said rheostats, a set of segments adjacent to one of said arms, a contact-finger on said arm adapted to slide on said segments, said segments being connected with the brake-solenoid and thence to one pole of the line and said rheostat-arm being connected with the other pole of the line.

95

7. In a controller for electric elevator-motors, the combination with the armature, of a pair of differential rheostats connected with the armature, a pair of connected rheostat-arms for said rheostats, a set of segments adjacent to one of said arms, a pair of auxiliary arms adjustably connected with said rheostat-arm, contact-fingers on each of said auxiliary arms adapted to slide on said segments, said segments being connected with the brake-solenoid and thence to one pole of the line and the rheostat-arm being connected with the other pole of the line.

100

8. In a controller for electric motors, the combination with the armature, of a pair of differential rheostats each terminal of each rheostat being connected with one armature-terminal, a pair of connected rheostat-arms,

105

110

115

120

125

130

for said rheostats, a pair of solenoids for operating said arms and a spring for holding said arms in their central or normal position.

9. In a controller for electric motors the combination of a pair of differential rheostats connecting with the armature, a pair of connected rheostat-arms for said rheostats, one of said arms being connected with one line-terminal, a pair of solenoids for operating said arms, solenoid-circuits connecting the line-terminals with said solenoids, an emergency-rheostat in said circuit, a solenoid for operating said rheostat in the circuit between said rheostat-arms and the line-terminal, the emergency-rheostat being adapted to throw resistance into the solenoid-circuit when there is an excess of current passing through the main rheostat-arm and means for controlling the solenoid-circuit.

10. In a controller for electric elevator-motors, the combination of a pair of differential rheostats connected with the armature, a pair of connected rheostat-arms for said rheostats, a set of segments adjacent to each

of said arms, one set connected to the brake-solenoid and the other connected with the shunt-winding, contact-fingers operated by said arms adapted to slide on said segments, a pair of solenoids for operating said rheostat-arms, circuits for said solenoids connecting with the line-terminals, a spring for bringing said arms to their central or normal position, an emergency-rheostat and an emergency-solenoid operating the same, the resistance in said emergency-rheostat being included in said solenoid-circuits, means for varying the solenoid-circuits, one of said rheostat-arms being connected with one line-terminal through said emergency-solenoid and the rheostat-arm being connected with the other terminal through the series winding of the motor.

Signed at Portland, Maine, this 6th day of March, 1902.
